UNITED STATES PATENT OFFICE.

WILLIAM CAREY, OF VIOLA, MICHIGAN.

FIRE-ESCAPE

SPECIFICATION forming part of Letters Patent No. 569,810, dated October 20, 1896.

Application filed December 31, 1895. Serial No. 573,921. (No model.)

To all whom it may concern:

Be it known that I, WILLIAM CAREY, a citizen of the United States, residing at Viola, in the county of Mackinac and State of Michigan, have invented a new and useful Fire-Escape, of which the following is a specification.

The invention relates to improvements in fire-escapes.

10 The object of the present invention is to improve the construction of fire-escapes, and to provide a portable apparatus which will be adapted to throw a grappling device over the top of a building in position to engage the same and which will form an elevator to enable persons to be quickly transferred from a burning building to the ground.

Another object of the invention is to enable the apparatus to be readily detached 20 from a building after the fire-escape has been used.

A further object of the invention is to provide means whereby the elevator apparatus, for carrying persons and property from a building to the ground, may be readily moved around a building in order to operate readily in connection with any particular window.

The invention consists in the construction and novel combination and arrangement of 30 parts hereinafter fully described, illustrated in the accompanying drawings, and pointed out in the claims hereto appended.

In the drawings, Figure 1 is a perspective view of a portable fire-escape apparatus constructed in accordance with this invention. Fig. 2 is a rear elevation of the same. Fig. 3 is a longitudinal sectional view. Fig. 4 is a transverse sectional view. Fig. 5 is an elevation illustrating the manner of anchoring 40 the apparatus to a building. Fig. 6 is a detail perspective view of the grappling projectile. Fig. 7 is a similar view of the auxiliary grappling device. Fig. 8 is a detail perspective view of the ladder. Fig. 9 is a detail view illustrating the manner of removing 45 the ladder from a building. Fig. 10 is a detail perspective view of the V-shaped hanger. Fig. 11 is a detail sectional view illustrating the manner of mounting the dogs 50 of the grappling projectile. Fig. 12 is an elevation of a portion of a building, illustrating

the manner of mounting an elevator adapted to be transferred from one window to another. Figs. 13 and 14 are detail views of one of the brackets which support the track-wire. 55 Figs. 15 and 16 are detail views of the brake for controlling the elevator.

Like numerals of reference indicate corresponding parts in all the figures of the drawings.

1 and 2 designate front and rear axles which have carrying-wheels journaled on them, and the rear axle 2 is provided with depending arms 3, hinged to a platform or base 4 of a supporting-frame. The platform or base of 65 the supporting-frame is provided with a contracted and tapering front portion 5, which is pivotally connected to the front axle to permit the carriage or vehicle to change its direction. The lower ends of the arms 3 are 70 bifurcated, and are pivoted to tongues of the base or platform, and are arranged in opposite recesses of the rear end thereof.

The supporting-frame which forms the body of the carriage or vehicle consists of the said 75 platform or base 4 and a substantially rectangular superimposed portion 6, supported at opposite sides by standards 7 and by a windlass-frame 8, which is mounted on the front axle. The sides of the top portion of the 80 frame form supports and afford seats for the firemen, and the front of the top portion accommodates the driver and is pivotally connected to the said windlass-frame.

A breech-loading gun 9 is mounted on the 85 rear axle, which forms trunnions for the same to permit the muzzle of the gun to be elevated to throw a grappling projectile 10 over the roof of a building, and the manner of hinging the rear axle to the frame facilitates the elevation and depression of the gun. The gun is provided with sights and has its pivoted breech-block 11 secured in its closed position by a catch 12, and mounted on the outer face of the breech-block is a resilient hammer 13 95 and a trigger 14, and the latter is hinged at one end to the breech-block, and is provided with an offset or shoulder to receive the hammer to hold the same drawn back preparatory to firing. The trigger is adapted to be 100 swung aside to release the hammer to discharge the gun. After the gun has been prop-

erly sighted it is retained in its adjustment by a slotted bar 9^a, supported at its lower end on the platform and passing through an opening of a block 9^b and engaged by a set-screw.

5 The charge of powder for firing the gun is introduced at the breech in the usual manner, but the grappling projectile 10 is inserted at the muzzle of the gun, and is provided with pivoted spring-actuated dogs 15, extending radially from the body of the projectile. The body of the projectile is provided with longitudinal slots 16, and the dogs 15 are pivoted in the slots and are provided at their inner ends, beyond the pivots, with heels or extensions, which are engaged by springs 15^a, located within the slots. The dogs are adapted to be folded within the slots when the projectile is inserted in the gun, and as soon as the projectile leaves the gun the springs throw 20 the dogs outward to cause the projectile to engage the building and to become anchored, as illustrated in Fig. 5. The grappling projectile is provided at its inner end with a recess 18, in which is pivoted one end of a link 19, and the latter is provided with a dog 20, and is adapted, when the projectile is discharged from the gun, to lie longitudinally thereof. When the gun is loaded, the link 19 is arranged in and projects through a slot 25 21 of the gun, the slot extends inward from the muzzle of the gun and is located at the lower side thereof, and a supplemental anchoring-bar 22 is connected with the link and is provided with dogs 23. The dogs 20 and 30 23 are pivoted in recesses and are thrown outward by springs 24, and their outward movement is limited by shoulders of the recesses, and the recesses of the grappling projectile 10 are also provided with shoulders, which are 35 40 engaged by the dogs 15.

The anchoring-bar is provided at its inward end with a pulley 25, around which passes a wire rope 26, and the latter is coiled on conical posts 27. The conical posts 27 are mounted 45 on the rear axle and are arranged parallel with the barrel of the gun, and when the projectile is fired therefrom the rope readily uncoils from the posts. The outer ends of the post are perforated for the reception of pins 50 28, which prevent the rope 26 from accidentally uncoiling.

One end of the rope 26 is secured to the main frame of the vehicle or carriage, and the other end of the rope is secured to the 55 ladder 29, which is provided at the upper ends of the sides with hooks 30, and which is adapted to be drawn upward to the roof of a building and to have its hooks engage the same, as illustrated in Fig. 5 of the accompanying drawings. After the ladder has been properly arranged in engagement with the roof of a building a firm and secure support or hanger is afforded, and the ladder is provided with a pulley 31, arranged in a suitable 60 65 block attached to the center of one of the rungs of the ladder. The wire rope 32 passes

over the pulley of the ladder, and has attached to it a cage 33, which is adapted to transfer persons from a building to the ground. One end of the wire rope or cable 70 32 is designed to be wound around a windlass of the apparatus, so that the cage may be conveniently hoisted and lowered, and, if desired, a pair of cages may be employed, as illustrated in Fig. 12 of the accompanying 75 drawings, one being secured to each leaf or portion of the wire rope 32^a. The cage and the ladder are designed to be constructed of suitable metal, and the cage is provided at its bottom with a perforation 34, adapted to receive a pin or stud 35 of the frame of the carriage, whereby the cage is detachably mounted thereon.

The ladder has its lowermost rung extended laterally to provide arms 36, to which may be 85 connected ropes for steadyng the ladder in guiding it to the top of the building as it is drawn upward by the rope 26, and centrally connected to the lowermost rung is a wire rope 37, which passes over a pulley 38 of a substantially V-shaped hanger 39, and the sides of the hanger are provided at their upper ends with teeth 40 for engaging the roof, and after the fire has been extinguished or it is desirable to remove the fire-escape from the building access is had to the roof by way of the ladder and the grappling projectile is disengaged. The V-shaped hanger is then placed in position for engagement with the roof adjacent to the ladder, which is adapted to be 95 drawn upward out of engagement with the roof by means of the rope 37, as clearly illustrated in Fig. 9 of the accompanying drawings.

The platform is provided in advance of the rear axle with conical posts 40^a, adapted to have ropes coiled around them. The platform also has mounted on it a support 41, which is provided with a hook 42, adapted to engage an eye 43 of the muzzle of the gun to 100 lock the gun in a horizontal position.

The windlass-frame 8 is provided at each side with a windlass 44, and it has forwardly-extending arms receiving a windlass 45, and a roller 46 is journaled on the windlass-frame 115 in rear of the windlass 45. At the rear face of the windlass-frame are arranged cleats for the attachment of ropes.

When two cages are employed, the wire rope or cable 32^a is controlled by a brake 47, 120 comprising a base-plate 48 and the lever 49, pivoted at one end in an opening or bifurcation 49^a of the base-plate 48, and provided at its other end with an enlargement 50, forming a treadle or foot-piece, and having intermediate of its ends a groove 51, adapted to receive the wire rope or cable 32^a. The wire 125 32^a is arranged in grooves 52 of the base, located at opposite sides of the opening or bifurcation, and the brake is preferably secured to the superimposed frame of the carriage at the foot piece or portion thereof in 130

order that it may be readily controlled by the foot of the operator.

The brake will enable the elevator to be readily controlled, and a loaded cage may be lowered as slowly as desired to avoid injury to persons or property.

When it is desired to transfer the elevator from one window or portion of a building to another portion thereof, a horizontally-disposed track wire rope or cable 53 is employed and preferably extends around the entire building, and the track wire rope or cable is supported by brackets 54, having a substantially V-shaped upper portion 55 and provided 15 below the same with grooves or notches 56 for the reception of the track wire or cable 53. These brackets are mounted on the exterior of the building at windows or other convenient places and each is provided above the 20 grooves or notches 56 with a substantially inverted-U-shaped recess or opening 57, in which is arranged a horizontally-disposed shield 58.

The shield 58 is inverted-U-shaped in cross-section and is constructed of sheet metal or other suitable material, and it forms a shed to protect the track wire or cable from the weather. The brackets are provided at their outer ends with entrance-openings communicating with the recesses and the grooves or notches, and the track wire or cable may be readily lifted out of the groove or notch of any one of the brackets and disengaged therefrom to permit the elevator to pass the bracket, and the wire or cable 32^a passes over a lower pulley of a hanger 59. The hanger 59 is provided with upper and lower pulleys or rollers. The upper pulley or roller is arranged on the track wire or cable, and the 40 lower pulley or roller receives the said wire or cable 32^a.

The elevator may be operated either by means of a windlass or by hand, as may be found necessary or desirable, and the carriage is preferably provided at its top with windlasses 60 for facilitating the operation of the elevator.

It will be seen that the fire-escape is simple and comparatively inexpensive in construction, that it is positive and reliable in operation, and that it will enable the inmates of a building to be quickly removed.

Changes in the form, proportion, and minor details of construction may be resorted to 55 without departing from the principle or sacrificing any advantages of the invention.

What I claim is—

1. In a fire-escape, the combination of a gun provided with a longitudinal slot extending inward from the muzzle and a projectile provided with a pivoted link adapted, when the projectile is in the gun, to extend through the slot, substantially as and for the purpose described.

65 2. In a fire-escape, the combination of a gun, provided with a longitudinal slot extend-

ing inward from the muzzle, a projectile provided with a pivoted link adapted to extend through the slot, and a supplemental anchoring-bar connected with the link, substantially as described.

3. In a fire-escape, the combination of a gun provided with a longitudinal slot, a grappling projectile having a recess and provided with spring-actuated dogs, a link pivoted in 75 the recess and adapted to extend longitudinally of the projectile, and also to project outward from the slot of the gun and provided with a dog, and a supplemental anchoring-bar connected with the link and provided 80 with dogs and adapted to carry a rope, substantially as described.

4. In a fire-escape, a ladder composed of sides having their upper ends curved and forming hooks for engaging a roof, and rungs 85 or steps connecting the sides, the lowermost rung being extended beyond both sides of the ladder and forming laterally-projecting arms 36 adapted to receive ropes for guiding the ladder, substantially as described.

90 5. The combination with a ladder provided with hooks for engaging a roof, of means for removing the ladder from a roof and lowering the same to the ground, said means comprising a substantially V-shaped hanger provided at the upper ends of its sides with teeth for detachably engaging a roof, a pulley arranged at the apex or lower end of the hanger, and a rope or cable arranged on the pulley and having one end attached to the bottom 100 of the ladder, substantially as described.

6. In a fire-escape, the combination of a frame, a front axle connected therewith, a rear axle provided with depending arms hinged to the frame, carrying-wheels mounted on the 105 axles a gun mounted on the rear axle, and conical posts mounted on the rear axle and arranged substantially parallel, substantially as described.

7. In a fire-escape, the combination of a 110 frame comprising a base, a top, and posts supporting the top, a front axle pivotally connected with the base, a windlass-frame mounted on the front axle and supporting the top 115 of the frame, a rear axle hinged to the platform, carrying-wheels mounted on the axles and a gun mounted on the rear axle, substantially as described.

8. In a fire-escape, the combination of a 120 frame comprising a platform, and a top having opposite sides and provided with a front connecting the sides, a front axle, a rear axle hinged to the frame, carrying-wheels mounted on the axles a gun mounted on the rear axle, and a fastening device arranged at the front 125 of the platform and adapted to lock the gun in a horizontal position, substantially as described.

9. In a fire-escape, the combination of a 130 frame, a cable carried by the frame, a base-plate having a longitudinal opening and provided with grooves at opposite sides of the

opening to receive the cable, and a lever fulcrumed at one end in the opening, provided intermediate of its ends with a groove to receive the cable and having at its other end a 5 foot-piece arranged to be engaged by the foot of a person, whereby the cable is controlled, substantially as described.

10. In a fire-escape, the combination with a track wire or cable, of a series of brackets 10 provided with grooves or notches 56 receiving the track wire or cable, said brackets being provided above the grooves or notches with inverted-U-shaped recesses and having entrance-openings at their outer sides commu-

nicating with the recesses or grooves and the 15 notches, to permit the track wire or cable to be disengaged from the bracket, and a shield substantially U-shaped in cross-section arranged in the recesses of the brackets and disposed over the track wire or cable, sub- 20 stantially as described.

In testimony that I claim the foregoing as my own I have hereto affixed my signature in the presence of two witnesses.

WILLIAM CAREY.

Witnesses:

M. HOBAN,
C. W. BERTCH.
